UNITED STATES PATENT OFFICE.

SUMNER TAINTER, OF WASHINGTON, DISTRICT OF COLUMBIA.

TELEPHONE-TRANSMITTER.

SPECIFICATION forming part of Letters Patent No. 336,173, dated February 16, 1886.

Application filed April 20, 1885. Serial No. 162,777. (No model.)

To all whom it may concern:

Be it known that I, SUMNER TAINTER, of Washington, in the District of Columbia, have invented a new and useful Improvement 5 in Telephone-Transmitters and Station Apparatus, which improvement is fully set forth in the following specification.

This invention relates more particularly to a transmitting or station apparatus for telephone-lines, in which the variable resistance or current-regulator is a sensitive jet of conducting-liquid, a part of which jet is included in the circuit of the galvanic battery or other source of electrical energy; but it may also be 15 applied, at least in part, to jet-translating apparatus generally, and possibly to other purposes.

The term "jet-translating" apparatus is applied to apparatus for translating or transferring 20 sonorous vibrations from one medium to another through a sensitive jet, such as described in the applications of C. A. Bell, filed May 1, 1884, and officially numbered 129,946, 129,947, and 129,948, upon which the present 25 invention may be regarded as an improvement.

The main object of this invention is to produce a suitable jet by a compact arrangement of devices adapted to practical use in a telephone-station. To this end, instead of employing a hydrostatic column to supply the jet-liquid under a head due to its height, the proper pressure is applied through a body of confined air, which is suitably compressed by 30 one or more springs or weights. Sometimes an automatic governor is employed to control the pressure which the air exerts upon the jet-liquid. In order to stop the jet when the use 35 of the apparatus is concluded, the air is allowed to escape by opening a valve. Preferably this is effected automatically by combining the valve with a movable telephone-support, so that the weight of the hand-telephone 40 opens it, the closing of the valve being effected when the hand-telephone is removed by a retractile spring. The electrical contacts for connecting in and cutting out the telephonic instruments may of course be combined with the telephone-support, so that the latter acts 45 as a switch, as usual; but it is preferred to combine a switch with the air-compressor or device for operating the same. The contacts

made in compressing the air will be broken and new contacts automatically established on replacing the hand-telephone; but they will 55 also be changed when the supply of compressed air is exhausted by the use of the apparatus, and of this fact the cessation of sounds in the telephone will give notice.

In the accompanying drawings, Figure 1 is 60 face view in sectional elevation of a telephone-station apparatus embodying the invention; Fig. 2, a sectional elevation on line *x x*, Fig. 1, looking to the right; Fig. 3, a sectional view on line *y y*, Fig. 2, looking upward, and Figs. 65 4 and 5 detail views in horizontal and vertical section, respectively. Fig. 6 is a central vertical section of another form of compressor, which may be used in place of that shown in Figs. 1, 2, and 3. Fig. 7 is a back view (with the back 70 of the telephone-case removed) of another form of station apparatus also embodying the invention or a part thereof. Fig. 8 is a sectional elevation on the vertical center line of Fig. 1, looking to the right; Fig. 9 a partial 75 view in sectional elevation in a plane parallel to that of Fig. 1, but looking in the opposite direction, and Fig. 10 a detail view in horizontal section.

Like letters indicate like parts of the different apparatus, which are all of my own invention.

A is the box or case in or on which all the parts are placed. Referring to Figs. 2 and 3, there is a collapsible air-tight bag, B, of soft 85 rubber, whose bottom is fastened by cement or otherwise to the back of case A, and whose top is similarly fastened to the spring-actuated follower C. The follower is guided in its movements by the standards 8, which pass 90 through holes in the corner of the follower. Pins 1, fixed in the partition 2, project into holes in the posts 3 on the follower. These posts are preferably allowed a certain freedom of movement to prevent binding, the screws, 95 which pass through the follower and into the lower part of the posts not being driven in, so as to keep the posts rigid. A spiral compression-spring, D, surrounds each post, and tends to force the follower C to the back of case 100 A, and thus compress the bag B. To withdraw the follower against the pressure of the springs, it is connected by the lever 4 and chain 5 with the flanged wheel 6 on shaft 7. The

partition 2 is fastened to the back of case A by the standards 8, which have retaining-nuts at the ends. The lever 4 is fulcrumed in the lower end of link 9, whose upper end is pivoted to the stationary piece 10 on the partition 2. The connection between the follower C and lever 4 is made through the bridge-piece 11, which is fastened to the follower, and to which the lever is pivoted. The chain 5 is wound upon the wheel 6 by turning the shaft 7 through the crank 25. Stops 12 are provided to limit the motion. When the follower C is moved to expand the bag B, air enters the latter by way of the valve 13, coupling 14, pipe 15, and tubular coupling 16. This tubular coupling has a flange on the inner (left-hand, Fig. 2) end, which is inserted in a hole in the top of the bag. A cap, 18, screwed on the outer end of the coupling and bearing upon the outer end of the sleeve 17, clamps the rubber of the bag between the flange and the inner end of said sleeve. An exterior flange on the sleeve rests upon the follower. The valve 13 (see Fig. 4) has a light disk, 24, for closing the inlet when the bag B is compressed, but opening freely when it is expanded. The valve is preferably inclined, so that the disk is slightly out of the vertical. Gravity thus acts to close the valve, while at the same time the disk does not have to be lifted bodily but only tilted in order to open it. When the bag B is compressed by the springs D, the air is forced under pressure through the coupling 16, pipe 15, coupling 14, chamber of valve 13, pipe 19, pressure-governor E, and pipe 20, into the upper part of the reservoir or chamber F. This chamber contains the jet-liquid, which, as soon as pressure is applied to the surface thereof, mounts through the filter G and pipe H to the jet-tube I. The pressure-governor E has a diaphragm, 26, of thin sheet-rubber, which is clamped at the edges and has attached to it a flat metal disk, 27, and also a pin, 28, against whose enlarged end (right hand, Fig. 5) the pressure-regulating valve 30 is held by the spiral compression-spring 34. The pin 28 passes through the center of the diaphragm 26 and disk 27, which are clamped together by the nut 29. The pin projects through the case of the governor, and is acted upon by the short arm of the weighted lever 31 in the direction tending to open the valve. The lever 31 is fulcrumed in the back of the governor-case, and the weight 32 is adjustable on the long arm thereof. The outer end of this arm plays in the slot 33 in the angle piece or bracket on partition 2. The pressure of the air on the jet side of the pressure-regulating valve against the governor or diaphragm 60 establishes an equilibrium between the antagonistic forces of the weight 32 and spring 34. The reservoir or chamber F is formed, as shown, in the lower half of a box, (say, of hard rubber,) and is cut off from the chamber K by the horizontal partition 35. This arrangement is preferred to that of a separate box for each chamber, because more compact; but it is not

essential. A filter, G, is placed in the jet-supply pipe. It consists of a cylinder (say of glass) cemented into the partition 35, filled with cotton, wool, or other suitable filtering material, and closed at the bottom by a perforated plug of hard rubber. The jet-tube I is set in a cup, 37, which closes the upper end of the glass protecting-tube 38, whose lower end is set in the hard-rubber base 39. The jet-tube is adjusted by the four set-screws 40, so that the jet plays properly on the electrodes set in the base 39, and the said jet-tube is then retained in that position by filling the cup 37 with liquefied cement, which hardens on cooling. The electrodes consist of a metal wire, 41, preferably of platinum, which passes axially through a seat in the center of the base 39, and a metal ring, 42, which surrounds the upper end of said seat, and is insulated by the same from the inclosed electrode 41. The jet plays upon the central electrode and spreads out in a thin film, which makes contact with the annular electrode and completes the circuit between them. The waste-pipe 43 carries the liquid which runs off the electrodes into the upper chamber, K, from which it passes through the pipe 44 into the lower chamber, F, when the air-pressure in the latter is relieved. When pressure is applied, the bottom of the pipe 44 is closed by the valve-disk 45, which at other times is supported on pins projecting inward from the ring 46, secured on the lower end of said pipe. The electrode 41 is connected by the wire 47 with the spring-contact 48. The electrode 42 is connected by the wire 49 with one terminal of the hand-telephone L, the other terminal being connected by wire 50 with the binding-post 51, with which one end of the line-wire is connected. The other end of the line-wire is connected with binding-post 52, and by this through the wire 53 with the sliding switch 54, which is attached to the partition 2 by screws passing through slots in the switch, and is shifted by the cam 55 on the shaft 7, acting against one of the edges 56. The spring-contact 57 is connected by wire 58 with the binding-post 59, to which the branch wire containing the signaling apparatus T is led. From the pipe 20 a branch pipe, 60, extends to the bottom of the case, and is there closed by the valve 61, which is formed by a disk attached to a projection on the telephone-support M. A spring, 62, keeps the valve closed, except when the telephone-support is drawn down, as it would be by the weight of the hand-telephone when suspended therefrom. The liquid used is preferably distilled water, acidulated with about one part in three hundred, by volume, of pure sulphuric acid. To prevent the liquid from escaping when the apparatus is carried, a tap, 63, is provided for closing the pipe 20, and also a screw-plug, 64, for closing the openings 23, through which the upper chamber communicates with the outside air. The face of the telephone-case is provided with a mouth-piece, 65, behind which is fastened a vibratory plate

or diaphragm, N, of wood. It is fastened at the four corners (see Figs. 2 and 7) to the face of the case, a washer being interposed. At the back of the plate or diaphragm is a bridge, 66, which bears against the tube 38, and assists in communicating the vibrations to the jet.

The operation is as follows: After the central office or another station has been called in any ordinary or suitable way the operator turns the crank 25, and before releasing it takes off the hand-telephone from its support, so that the branch pipe 60 is closed by a valve, 61. The line, which previously included the signaling branch, is now completed (provided the crank has been released) through the switch 54, contact 48, the electrode 41, the included part of the jet, the electrode 42, and the hand-telephone L. The galvanic battery is included in the line at any point, preferably in an exchange at the central office. On releasing the crank 25 the springs D compress the bag B, and (the valve 13 closing automatically) force the air through the pressure-governor E and the connected pipes and couplings into the chamber F. The compressed air forces the liquid through the jet-tube I, and causes the jet to play upon the inner electrode, and spread in a film over the outer one. Speech uttered or other sounds made in the vicinity of the mouth-piece 65 will be reproduced in the hand-telephone L, in consequence of the variations in current due to the vibrations imparted to the jet and the consequent variations in the resistance of that part of the jet included between the electrodes. When the operator has finished talking, the hand-telephone L is replaced on its support M, its weight then opening the valve 61, and allowing the air to escape rapidly from the bag B. The jet soon stops, and the liquid all runs back into the lower chamber, F. When the air has about all escaped, the switch 54 is shifted by the rotation of the cam 55 into the position shown in Fig. 1, whereupon the telephonic instruments are cut out of circuit.

The compressor shown in Fig. 6 resembles a gasometer, the edges of the bell P being sealed with mercury instead of water. The bell slides in the inclosing-cylinder 70, which fits tightly at the bottom in an annular groove in the base 71. The shell 72, in an annular form, also makes a tight joint with the base at its lower edges. The mercury is inclosed between the outer wall of the shell 72 and the inclosing-cylinder 70. In the middle of the bell is a tubular chamber, 73, which fits within the shell 72, and in which is placed the spiral compression-spring D, and also, at the lower end thereof, the valve-disk 74 and its seat 75. The compression-spring is confined between the valve-disk 74 and the top 76 of a box, in which the compressor is placed, and of which the base 71 forms the bottom. The chain 5 is fastened at its lower end to the said disk. When the chain is wound upon the wheel 6, it first lifts the valve-disk off its seat, and thus establishes

free communication through the valve between the external air and the interior of the bell P. When the valve has been lifted from its seat, 70 the flange 77 on the valve-disk engages the flange 78 on the seat, and lifts said seat, and consequently lifts also the bell P, to which the valve seat is fastened. When the crank on shaft 7 is released, the first effect of the spring 75 D is to close the valve, and then to force down the bell P, so as to expel the air under suitable pressure through the pipe 79, which may convey it to the reservoir F with or without passing through the pressure-governor. 80

The compressor shown in Figs. 7, 8, and 9 is formed by a drum, Q, mounted loosely on the shaft 80, and provided with an annular space at the periphery, in which is a body, 81, of mercury, which acts as a fluid-piston. The shaft 80, is journaled in stationary bearings, and is provided at the front end with a crank-arm, 25, for turning it by hand. At the back end a disk, 82, is fixed on the shaft, and also a barrel or holder, 83, for the spring D, which, 90 as shown in these figures, is a volute spring, like that of a clock or watch. Of course a weight arranged like a common clock-weight could be used instead of the spring. The inner end of this spring is fastened to the sleeve 95 of the barrel, and the outer end to a pin fixed on the pendent bracket 84, in which the rear end of the shaft is journaled. The drum Q has a pin, 85, which plays in a slot in the disk 82. The shaft is capable of a movement independent of the compressor-drum. Advantage is taken of this free movement to operate the valve 86, so as to open or close the outer end of the pipe 87. The valve is attached to the outer end of an arm, 88, fixed on the shaft 105 80. When the shaft is turned in the direction to wind the spring D, the valve is lifted away from the end of pipe 87 before the drum Q is turned by the upper end of the slot striking the pin 85. When crank 25 110 is released, the spring turns the shaft independently until the valve 86 is pressed against the end of the pipe 87, whereupon the pressure against said pipe turns the drum also. The annular space of drum Q is not continuous, 115 but is divided at one point by the partition 89. The pipe 87 opens into the annular space (see Fig. 7) on what may be called the "compression side of the mercury," as it is on this side that the air is compressed. The 120 annular space on the other side of the mercury is always in free communication with the external air through the pipe 90. (See Fig. 9.) The object of curving the pipes 87 and 90 is to prevent the escape of the mercury. The pipe 125 20, leading to the chamber or reservoir F, passes through an opening in the shaft 80, and communicates with the pipe 87 near its outer end. At 95 is a counterbalance-weight. When the shaft 80 is turned, (to the right, as shown in 130 Fig. 9,) the movement first lifts the valve 86, and then rotates the drum Q. As the drum rotates, the air is expelled through the pipe 90 from the space in front of the mercury, and is

drawn through the pipe 87 into the space behind it. When about two-thirds of a revolution has been made, the crank 25 is released, and the spring D, which is now wound, turns back the shaft 80 until the pipe 87 is closed by the valve 86, and then it turns the drum Q, (to the left, as shown in Fig. 9.) The air which has been drawn in through the pipe 87, having no escape, except through the pipe 20 into the chamber F, is compressed until its pressure against the partition 89 balances the tension of the spring D. This pressure is then maintained constant, the air escaping and the drum turning just as fast as the liquid is forced from the reservoir F through the jet-tube I. The rest of the apparatus is the same as or so nearly like that shown in Figs. 1 and 2 that no further description is necessary, except to state that the switch 54 is shifted in the direction to cut out the telephonic instruments by the pin 92, and in the direction to connect them in circuit by the pin 93, both on the drum Q, and that the spring 94 on the switch, which the end of the pin 94 rubs against, acts as a brake when the spring D commences to unwind, to prevent the drum Q being carried with the shaft 80 until the valve 86 has been pressed firmly against the end of pipe 87.

It is evident that various other modifications may be made without departing from the spirit of the invention; also, that parts of the invention may be used separately. It is also to be observed that the invention is not limited to the forms, proportions, or materials described.

Having now fully described my said invention, what I claim is—

1. The combination of the jet-tube, reservoir, and supply-pipe of the spring-actuated air-compressor, and the pipe connecting the same with the said reservoir, substantially as described.

2. The combination of the spring actuated air - compressor, the pressure - governor, and the connected pipes with the liquid-reservoir, the jet-tube, and the jet-supply pipe, substantially as described.

3. The combination, with the reservoir, the jet-tube, the jet-supply pipe, and the means for impressing vibrations on the jet, of a source of compressed air communicating with the said reservoir to force the liquid through the jet-tube, substantially as described.

4. The combination of a source of compressed air and the liquid - reservoir with the filter, the jet-supply pipe, and the jet-tube, through which the liquid in said reservoir is forced, and the means for impressing vibrations upon the jet, substantially as described.

5. The combination of the reservoir, the jet-supply pipe, and the jet-tube, and the source of compressed air with a receiver for the liquid after it has formed the jet communicating with the aforesaid reservoir through a check-valve, substantially as described. 65

6. The combination, with the electrodes, the jet-tube, and the jet-supply pipe, of a reservoir for containing the jet-liquid, and a source of compressed air for forcing it through the jet-tube, substantially as described. 70

7. The combination, with the jet-tube for producing a sensitive vibratory jet, and the reservoir and pipe for supplying liquid to said jet, of a source of compressed air for forcing the liquid through the jet - tube, and a valve 75 for letting out said air, when desired, to stop the jet, substantially as described.

8. The combination, in a jet-translating apparatus, with the source of compressed air for producing the jet, of the telephone - support 80 and the valve controlled thereby for releasing the air when opened, substantially as described.

9. The combination, with the spring-actuated air - compressor, of an electrical switch connected with the same, substantially as described. 85

10. The combination, with the air-compressor or and the electrical switch connected therewith, of the movable telephone - support and 90 the valve controlled thereby, for releasing the compressed air and causing the switch to be shifted on replacing the hand-telephone, substantially as described.

11. The combination, with the jet-tube and 95 its holder or cup, of the set - screw bearing against the sides of said tube for adjusting the position of the same, substantially as described.

12. A telephone-station apparatus comprising, in combination with the hand-telephone, the automatic electrical switch, and the telephone - support, a transmitting - instrument composed of a diaphragm or vibrating plate, a jet-tube to which the vibrations of said plate are communicated, electrodes arranged in the 105 jet, a spring-actuated air-compressor, a reservoir for the jet-liquid, a receiver for the liquid after it has passed through the jet, and the connecting pipes and valves, substantially as described. 110

In testimony whereof I have signed this specification in the presence of two subscribing witnesses.
